UNITED STATES PATENT OFFICE.

DAVID S. KENNEDY, OF BROOKLYN, NEW YORK, ASSIGNOR TO MERGEN-
THALER LINOTYPE COMPANY, A CORPORATION OF NEW YORK.

LINOTYPE-MACHINE.

SPECIFICATION forming part of Letters Patent No. 792,993, dated June 20, 1905.

Application filed January 19, 1905. Serial No. 241,832.

To all whom it may concern:

Be it known that I, DAVID S. KENNEDY, of Brooklyn, county of Kings, and State of New York, have invented a new and useful Improvement in Linotype-Machines, of which the following is a specification.

My invention has reference to linotype-machines of the general organization represented in United States Letters Patent No. 557,000, wherein the escapements controlling the delivery of the matrices from the mouth of the magazine are actuated through vertical reeds or bars from a keyboard mechanism of the character shown in United States Letters Patent No. 530,931. In this mechanism the reed, extending downward from each escapement and urged constantly downward by a spring, is lifted at intervals by a pivoted yoke containing a lifting-cam, which acts periodically on an underlying and constantly - turning roller. The magazines of these machines are removable that they may be replaced by others containing matrices for different faces. Preparatory to the removal of the magazine it is necessary that the upper ends of the reeds should be drawn backward and unhooked from the escapements in order to release the latter, and to this end they are mounted in a movable guide. Before unhooking the reeds it is necessary to give them a temporary support, as otherwise they will fall so far that it is impossible to reengage their upper ends with the escapements after the new magazine is placed in the machine. These reeds have been ordinarily supported by thrusting a bar into the frame transversely beneath the series of reeds. In practice it is found that negligent or ignorant attendants will frequently omit to introduce the supporting-bar and that in consequence the reeds will fall, as above stated, so that much time and labor is required in lifting them individually to their operative positions.

The first object of the present invention is to prevent the reeds from being disengaged unless they are first sustained or locked in the elevated position, and to this end it consists, broadly, in combining with the guide for the upper ends of the reeds or with other means

for disengaging the reeds from the escapements a locking device controlled by the reed-supporting bar or its equivalent.

The second part of the invention has in view the lifting and supporting of the entire series of reeds at one operation by mechanism forming a permanent part of the machine, and to this end it consists of a lifting-bar lying transversely across and adapted to engage all of the reeds and combined with a hand-lever or like mechanism, by which it may be raised to sustain the reeds.

The third part of the invention has in view the automatic and positive locking of the matrices within the magazine before it is removed from the machine, so that they may not be accidentally released when the magazine is off from the machine. In its preferred form this mechanism consists of a rock-shaft mounted in the magazine in position to lock all of the escapements and combined with an actuating device on the machine of such character as to effect the automatic locking of the escapements before the magazine can be removed, this device being preferably connected with the before-mentioned device for locking the reed-guide.

Figure 1 is a perspective view of a portion of the ordinary linotype-keyboard mechanism, together with the delivery end of the magazine and attendant parts, with my guide-locking device incorporated therein in its most simple form, the parts being in operative position. Fig. 2 is a similar view of the parts with the reed-supporting bar inserted and the reed-guide unlocked to permit the disengagement of the reeds from the escapements. Fig. 3 is a side elevation, partly in section, of the keyboard mechanism, the lower end of the magazine, and the devices for lifting and sustaining the reeds in series, for locking the reed-guide, and for locking the matrices, the parts being in position to permit the operation of the machine. Fig. 4 is a perspective view of the parts shown in the preceding figure with the parts unlocked.

Referring to Figs. 1 and 2, A represents portions of the main frame; B, the lower end of the stationary inclined magazine, consist-

ing of parallel separated plates containing grooves to guide the upper and lower edges of the matrices C. D represents the oscillating escapement-levers, one for each magazine-
5 channel, mounted on its under side and each provided with two dogs or pawls, which are projected upward alternately into the magazine to permit the delivery of the matrices one at a time. E represents the series of up-
10 right reeds or rods mounted at their upper and lower ends in the guides F and G, having their upper ends arranged to engage from the rear with the respective escapements D. The upper reed-guide F is mounted on horizontal
15 pivots f, so that it may be swung forward and backward in order that the reeds may be thrown backward from their operative position (shown in Fig. 1) to the position shown in Fig. 2 out of engagement with the escapements. The reeds E terminate at their lower ends above the inner ends of corresponding yokes H, mounted to rise and fall on fixed pivots h at their outer ends. Each yoke is
20 slotted vertically to receive a cam I, turning
25 on a pivot i in the yoke. J J represent two continuously-rotating rubber-covered rolls extending transversely of the keyboard beneath the respective series of yokes and cams for the purpose of engaging and turning the
30 cams I. Angular dogs K serve to hold the respective yokes normally at such height as to maintain the cams I out of engagement with the underlying rolls, the cams being in the meantime prevented from rotating by the
35 engagement of internal shoulders with fixed stop-pins L. Each dog K is connected by a vertical slide M with a finger-key lever N. When a finger-key is actuated, the dog releases the corresponding yoke H and permits
40 it to fall until its cam I disengages from the stop L and rests upon the underlying roller. The frictional engagement of the roll causes the cam to turn on its center, the result of which is that the cam lifts the yoke above its
45 original position, causing it in turn to lift the reed E and release the escapement D, the position of which is immediately reversed by the spring d bearing thereon. The dog resumes its original position under the yoke,
50 which is arrested in its descent, while at the same time the cam is arrested in its rotation, so that these parts stand again in their original position, the reed E being at the same time drawn downward by a spring O, so that
55 the escapement D is compelled to resume its first position.

All of the foregoing parts are constructed and operate as usual.

My first improvement relates to means for preventing the reeds E from falling below the level of the escapements when they are disengaged therefrom, as shown in Fig. 2. In the form shown the locking device consists simply of an arm P, fixed rigidly in the frame
65 in position to engage a stud Q, applied for

the purpose to one of the reeds E or to a special sliding bar mounted in like manner. When the parts are in operative position, the stud Q stands in front of the locking-arm P, so that it is impossible to swing the reed-guide 70 and reeds backward.

R represents the usual reed-supporting bar, which is separate or distinct from the machine. Its inner end is beveled and it is adapted to be thrust through an opening in 75 the main frame into position beneath the series of yokes H in order to hold them and the reeds resting upon them at or slightly above their ordinary operative position, as shown in Fig. 2. I provide the bar with a raised surface r or otherwise form it in such manner that when thrust inward to support the reeds it will lift the reed or slide it across the locking-stud Q until the stud is above the locking-plate P, as shown in Fig. 2, the effect being to lift the parts free, so that the reed-guide F may be swung rearward in the ordinary manner to the position shown in Fig. 2.

The essence of my invention consists in providing means whereby the upholding of the reeds is rendered positively necessary prior to their disconnection from the escapements, and it is manifest that the details of construction to this end may be widely varied. 90

The reed-guide is held normally in position by a latch f², which is of ordinary construction and foreign to the present invention. This latch of course requires to be unlocked, as usual, before the guide can be moved. 100

Referring to the second part of my invention, (illustrated in Figs. 3 and 4,) the escapements, reeds, reed-guide, &c., are of the same general organization as in the preceding figures, like parts being indicated by like letters in all the figures. For the purpose of locking the entire series of escapements before the magazine is removed from the machine to prevent accidental release of the matrices I mount in the under side of the magazine the transverse rock-shaft S, cut away on one side in such manner that when turned into the position shown in Fig. 3 it permits the free action of the escapements, but when turned into the position shown in Fig. 4 it 105 bears upon their rear ends and locks the entire series rigidly against movement, so that the escapements in turn lock the matrices positively within the magazine. This device in itself is not claimed as a part of the present invention, which relates to the means for actuating this device or its equivalent. I provide this rock-shaft on the outer end with a crank-arm s, entering a slot in the horizontal upper end of a bar T, mounted to slide vertically in 110 guides on the main frame. The lower end of this bar is provided with a stud t, adapted to enter a notch on a hand-lever U, mounted on one end of a horizontal rock-shaft V, sustained in the main frame, so that whenever 115

the lever is raised the intermediate parts will turn the rock-shaft and lock the escapements and in like manner unlock them when the lever is depressed. Across the series of reeds 5 near their lower ends I extend a horizontal bar W, carried at its ends by vertical guides w on the main frame and adapted to enter notches v^2 in the rear edges of the reeds, these notches being of such width vertically as to 10 permit lost motion of the parts that the reeds may serve their ordinary function while the bar is at rest. This bar serves to lift and sustain the reeds in the same manner that they are sustained by the bar R in Figs. 1 and 2. 15 In other words, it is an equivalent to the removable bar R, but a permanent member of the machine. The guides at the ends of the bar are formed with shoulders or projections w^2 , overlying crank-arms v , secured to the 20 rock-shaft V, as plainly shown. When the hand-lever is thrown upward, the cranks v underride the projections w^2 and lifting the bar W cause it to lift and sustain the entire series of reeds. The formation of the arms 25 w^2 and the location of the shaft V are such that after the lever is raised, as shown in Fig. 4, the parts will remain in place, and thus lock the reeds in their elevated position. It will be observed that this upward movement of the lever to lift the reeds also causes 30 the action of the escapement-locking device. The reed-guide F is locked in position by means of the stud Q and fixed locking-plate P until the reeds are elevated to carry the 35 stud out of engagement with the plate, as described in connection with Figs. 1 and 2. The upward movement of the lever serves the threefold purpose of lifting and sustaining the reeds, of unlocking the reed-guide from 40 the plate P that the reeds may be disengaged from the escapements, and of locking the escapements, so that the accidental release of the matrices is prevented. When the magazine is to be removed from the machine, it is 45 necessary to disengage the crank s from the actuating-arm T. To this end the upper horizontal end of the arm is in the form of a sleeve fitting over the horizontal end of the body portion and arranged to be moved forward and backward by hand, so that it may 50 be engaged and disengaged at will. This sliding portion is slotted and secured by a thumb-screw, as shown. The reed-guide F may be provided with an upwardly-extending 55 arm f^3 in position to underride the crank s when the guide is thrown backward, as shown in Fig. 4, that the interlocking of these parts may prevent the reed-guide F from being moved until the crank has been turned upward out of the path of the arm f^3 to lock the 60 escapements, and, on the other hand, the crank will be prevented from turning to unlock the escapements until the guide has been restored to its normal operative position and 65 the arm f^3 thereby carried from under the

crank-arm. When the lever U is turned to its uppermost position, it will disengage from the stud t . In order prevent the bar T from falling out of position, it is notched and a spring-latch t^2 mounted on the frame to enter the notch, as shown in Fig. 3. It will be observed that when the handle U is raised the reeds are lifted and locked in an elevated position, the escapements locked to hold the matrices within the magazine, and the reed-guide unlocked to permit the disconnection of the reeds from the escapements. In this manner the operator is not only enabled but compelled to place the parts in positions of safety before removing the magazine, and this without appreciable loss of time. The return movement of the handle U after a magazine has been placed in position and after the reed-guide F has been swung forward to its operative position will restore the various parts to the operative condition. The handle U lies adjacent to the keyboard in such position that it may be conveniently reached and operated by the compositor. This handle and its connections for lifting and locking the reeds in the elevated position are of great advantage aside from the other parts with which they coöperate in that they enable the operator to lock the reeds up and render the keyboard inoperative. The improper release of the matrices by the accidental or mischievous operation of the keys in the absence of the operator is thus prevented.

Having described my invention, what I claim is—

1. In a linotype-machine, escapements controlling the discharge of matrices, escapement-actuating reeds, a guide for the reeds movable to permit the disengagement of the reeds from the escapements, locking mechanism to prevent the movement of the guide when the reeds are in operative position, and means for unlocking the parts when the reeds are raised above the operative position.

2. In a linotype-machine, the magazine and its escapements, in combination with the escapement-actuating reeds, a movable guide for the reeds, a locking device for said guide to prevent its movement when said parts are in normal positions and means for automatically unlocking the parts when the reeds are raised above their normal position.

3. In a linotype-machine, the combination of the escapements to control the release of matrices, detachable actuating-reeds, a movable reed-guide, and a stationary locking member coöoperating with one of the reeds to prevent the movement of the reed-guide until the reed is raised to an abnormal position.

4. In combination with the escapement D, a movable reed-guide F, a locking device P, and a reed extended through the guide, detachably connected with the escapement and adapted to engage when in operative position

with the lock P, whereby the movement of the guide and disengagement of the reed is prevented until the reed is lifted and sustained above its normal position.

5 5. In a linotype-machine, the escapements, their actuating-reeds and the movable reed-guide, in combination with means for locking the guide while the reeds are in normal positions, and means for lifting and sustaining 10 the reeds and unlocking the guide.

6. In combination with the escapements, the detachable reeds, the movable reed-guide, means for locking the guide, a transverse bar arranged to lift and sustain the series of reeds, 15 and means, forming a permanent part of the machine, for lifting and sustaining said bar and simultaneously unlocking the reed-guide.

7. In a linotype-machine, in combination with the escapement-actuating reeds E, a transverse lifting and supporting bar W, and a rock-shaft provided with an operating-handle, and with means for lifting and automatically sustaining the bar W, whereby the entire series of reeds may be raised by a single action 20 and sustained above their normal positions.

8. In combination, the escapement-actuating reeds E, containing notches e^2 , the transverse bar W having vertical end guides w , and a rock-shaft V provided with an operating-handle and with arms v , adapted to raise 25 and automatically sustain the bar W and the reeds.

9. In combination with the series of escapement-actuating reeds E, a transverse rock-shaft B, provided with an operating-handle, and intermediate connections for lifting the 30 reeds and locking them in their elevated position.

10. In a linotype-machine, a removable 35 magazine, provided with escapements and means for locking them, detachable escapement-actuating reeds, and means for lifting and sustaining the reeds and operating the escapement-locking devices, whereby the re-

moval of the magazine is prevented until the 45 escapements have been locked to retain the matrices and the reeds set in position to permit reengagement when the magazine is restored.

11. In combination with the magazine containing the escapements and their locking-shaft S, the escapement-actuating reeds, their movable guide, means for locking the guide, means for lifting the reeds and unlocking the 50 guide, and a connection from the last-named 55 mechanism to the escapement-locking device.

12. In combination with the reeds E and the rock-shaft F, arranged to lift the same and provided with an operating-handle, the escapement-lock S, its crank-arm, and the bar 60 T, arranged to be operated in connection with the rock-shaft.

13. In combination with the escapement-locking device S and the lever U, an intermediate bar having an adjustable upper end, to 65 permit engagement with and disengagement from the escapement-lock.

14. In a linotype-machine, the escapements, their locking device, their actuating-reeds, and the movable reed-guide, in combination with 70 a manual device and connections therefrom for lifting the reeds, locking the escapement and unlocking the reed-guide, whereby the operator is enabled and compelled to put the various parts in positions of safety before removing the magazine.

15. In combination with the magazine, its escapements and their locking-shaft provided with a crank-arm, the actuating-reeds and their movable guide F, provided with an arm 80 f^3 interacting with the escapement-lock.

In testimony whereof I hereunto set my hand, this 14th day of January, 1905, in the presence of two attesting witnesses.

DAVID S. KENNEDY.
